(57) **CLAIM**

The ornamental design for a sorting machine for handling goods, as shown and described.

DESCRIPTION

The patent or application file contains at least one drawing executed in color. Copies of this patent or patent application publication with color drawing(s) will be provided by the Office upon request and payment of the necessary fee.

FIG. 3.1 is a front elevation view of a first embodiment of a sorting machine for handling goods showing our new design;

FIG. 3.2 is a rear elevation view thereof;

FIG. 3.3 is a right side elevation view thereof;

FIG. 3.4 is a top plan view thereof;

FIG. 3.5 is a front perspective view thereof;

FIG. 3.6 is a rear perspective view thereof;

FIG. 4.1 is a front elevation view of a second embodiment of a sorting machine for handling goods showing our new design;

FIG. 4.2 is a rear elevation view thereof;

FIG. 4.3 is a right side elevation view thereof;

FIG. 4.4 is a top plan view thereof;

FIG. 4.5 is a front perspective view thereof; and

FIG. 4.6 is a rear perspective view thereof.
